UNITED STATES PATENT OFFICE.

ROY H. ROWLAND, OF VALLEY JUNCTION, IOWA.

GAME-BOARD.

1,359,108.

Specification of Letters Patent. Patented Nov. 16, 1920.

Application filed March 16, 1920. Serial No. 366,420.

To all whom it may concern:

Be it known that I, Roy H. Rowland, a citizen of the United States, and a resident of Valley Junction, in the county of Polk and State of Iowa, have invented a certain new and useful Game-Board, of which the following is a specification.

The object of my device is to provide a game, which is adapted to be played upon a table, such as is commonly used for playing billiards, which is of simple, durable and inexpensive construction.

A further object of my device is to provide a game, whereby balls are rolled upon the game board until they reach a certain position, when gravity will cause them to roll down an inclined surface, the inclined surface being provided with a plurality of pockets for receiving the balls, and also with a series of spaced pins, which will cause the balls to travel in a zigzag path, while traveling down the inclined surface.

A further object of my device is to provide a game board, which is provided with a series of pockets for receiving balls, the pockets being so arranged that it will be an easy matter for the balls to become lodged in some of them, and quite difficult for balls to become lodged in some of the other pockets.

30 The score or number of points made by playing the game may be varied; that is, if a ball becomes lodged in one of the difficult pockets, twenty-five points are credited to the player, if the ball becomes lodged in some of

35 the less difficult pockets, ten points are credited, and if it becomes lodged in one of the easier pockets, then five points will be credited to the player. The device will ordinarily be played upon a billiard table with

40 fifteen balls, and the total score made by the fifteen balls will be the total number of points which the player will be credited with. The object being for the player to obtain the greatest number of points possible.

45 Still a further object is to provide a game board, which is to be used in combination with a billiard table and fifteen balls. The game being provided with a closure member for holding the entire number of balls, while

50 the game is being played, the closure member being adapted to be removed, when it is desired to remove the balls from the game board and start the next game.

Still a further object is to provide a game, 55 which requires some skill on the part of the player to cause the ball to travel at a certain

rate of speed to a certain point, at which point the ball then travels by gravity to various parts of the game board, the operator having no control of the ball after it reaches that point upon the board where gravity will cause the ball to roll.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a side elevation of a table with my improved game board shown thereon, parts of the table being shown in section in order to better illustrate the position of my device, when being used.

Fig. 2 shows a top or plan view of a portion of a table with my improved game board thereon.

Fig. 3 shows a sectional view taken on line 3—3 of Fig. 1, showing the track and guides through which the balls travel on the game board.

Fig. 4 shows an enlarged, detail, top view of one end of the guide members.

Fig. 5 shows a detail, sectional view 85 through one of the pins on the game board; and

Fig. 6 shows a sectional view taken on line 6—6 of Fig. 1.

In the accompanying drawings, I have 90 used the reference numeral 10 to indicate the ordinary table, which is provided with the legs 11.

The top of the table 10 is provided with a recess 12. The outer edges of the recess 12 95 are provided with a rubber cushion member 13. My improved game board is inclined at one end, resting on the bottom of the recess 12 and the other end resting on top of the cushion member 13. This is clearly shown 100 in Fig. 1 of the drawings.

My improved game comprises a base 14, which is provided with a curved guide member 15. The guide member 15 extends around the outer edge of the base 14 and is 105 of angle iron construction, as is shown in section in Fig. 3 of the drawings. The guide 15 is held to the base 14 by means of the screws 16.

Spaced inwardly from the curved guide 110 15 are the short guide members 17, which are secured to the base 14 by means of the

screws 18. The inner ends of the guides 17 are curved at 19 and the lower ends of the guides 17 are formed with the curved portions 20 thereon.

5 It will be seen that between the ends 15 of the guides 17 an opening is formed. I have used the reference character A to indicate generally the track or passageway formed between the guides 15 and 17.

10 The lower or forward edge of the base 14 is beveled at 21, so that the extreme forward edge of the base 14 will be substantially flush with the upper surface of the recess 12. This is substantially illustrated 15 in Fig. 6 of the drawings.

The base 14 is provided with a series of pockets 22, 23, and 24. The pocket 22 is near the upper portion of the game board and is substantially in between the ends of 20 the guides 17. The pockets 23 are near the center of the board, while the pockets 24 are near the extreme lower edge of the game board.

I have shown only one pocket 22, several 25 pockets 23, and a great number of pockets 24.

Spaced at various points on the surface of the base 14 are the pins 25. The pins 25 are formed with a small flange 26 and a screw-threaded portion 27. The screw-threaded portion 27 is designed to be received within an opening within the base 14 and to receive a nut 28 on its lower end.

30 The flange 26 rests against the upper surface of the game board, while the nut 28 rests snugly against the lower surface. By tightening the nut 28 on the screw-threaded portion 27, I am able to firmly hold the pins 25 in proper position. The pins 25 are so 35 placed upon the table, that it would be difficult for a ball to make a straight line in traveling from the upper portion of the base 14 to the extreme lower portion.

The track A is slightly wider than the ball 29, whereby some play and clearance is provided when the ball is traveling within the curved track A. The pockets 22, 23, and 24 are smaller than the ball 29, so that a ball 40 will not pass through, but merely become lodged or seated within the pockets.

50 Near the extreme lower edge of the base 14, I have provided a closure member 30, which extends in between the ends 20 of the guides 17. The closure member 30 is provided with the grooves 31, which receive the ends 20 of the guides 17.

The closure member 30 may be raised, whereby the balls which will be held upon the base may be easily removed therefrom, 55 and then the closure member 30 may be replaced in position, and thus prevent any of the balls, after they are on the game board, from again passing onto the table.

The way in which the game is played is to 60 place the balls somewhere upon the table

10 and forcing them by the use of a cue stick into the track or passageway A. If too much force is used in forcing the ball into the track A, it will be seen that the ball 15 will follow the curved guide 15 and pass 70 out at the opposite end of the game board. But if just enough force is used, the ball will lose its momentum about the time that it reaches the point on the track between the ends 19 of the guides 17. Gravity will then 75 cause the ball to pass down the inclined surface. During the passing or rolling of the ball from the upper portion of the base to the lower, there are some probabilities that the ball will become lodged in the pocket 80 22, but if it should fail to lodge in the pocket 22, then there is some chance that it will be received in the pockets 23. If it is not received in these pockets then, of course, the ball will be received in one of the pockets 24. The pins 25 prevent the balls from following a straight path, but cause them to move in a zigzag direction, which makes it very interesting in so far that after the ball once comes upon the game board, no 90 amount of skill on the part of the player will help make any sort of a score.

From the foregoing, it will be seen that the game is very interesting, and that the total score at the end of the game will vary 95 according to just where the balls have become lodged in the pockets.

It will be of course understood that the pockets may be arranged in various ways, and the number of points credited to the 100 player by the pockets may be varied in accordance with the desire of the players, but the principle of the game is the pocket 22 in which the ball will become lodged only a few times in a great number of plays will 105 give the operator or player a greater amount of credit, than if the ball will become lodged in the pockets 24. The pockets 23 will give the player less credit than the pocket 22, but yet more credit than the pockets 24, because 110 the chances of having a ball become lodged in the pocket 23 are much less than in the pockets 24. The total score made by the total number of balls used will be the total credit given each player.

115 Some changes may be made in the construction and arrangement of the various parts of my improved device without departing from the essential features and purposes of my invention, and it is my intention 120 to cover by my claims any modified forms of structure or use of mechanical equivalents, which may be reasonably included within their scope.

I claim as my invention:

125 1. A game adapted to be played upon a table, said game including a base set at an incline relative to the table and adapted to have one edge rest flush with the upper surface of the table, spaced curved guides 130

placed upon said base forming a track, the inner one of said guides being provided with an opening whereby balls traveling between said guides will pass out at the opening and 5 roll over the inclined base, and a closure member adapted to sit adjacent to the forward edge of said base and to be held in position between the lower ends of the inner guide whereby the balls will be held upon 10 the base after being played.

2. A game adapted to be played upon a table, said game including a base set at an incline relative to the table and adapted to have one edge rest flush with the upper surface of the table, spaced curved guides 15 placed upon said base forming a track, the inner one of said guides being provided with an opening whereby balls traveling between

said guides will pass out at the opening and roll over the inclined base, and a closure member adapted to sit adjacent to the forward edge of said base and to be held in position between the lower ends of the inner guide, whereby the balls will be held upon the base after being played, a plurality of 20 pockets formed in the surface of the base between the inner guide and the closure member, the pockets being designed to receive the balls traveling over the inclined base after they have left the track, the parts 25 being so arranged that it will be more difficult to have the balls lodge in some of the pockets than in others.

Des Moines, Iowa, March 2, 1920.

ROY H. ROWLAND
